UNITED STATES PATENT OFFICE.

JOHN C. McLAUGHLIN, OF NEW YORK, N. Y., ASSIGNOR TO UNDERWOOD TYPEWRITER COMPANY, OF NEW YORK, N. Y., A CORPORATION OF NEW JERSEY.

TYPE-WRITING MACHINE.

No. 839,408.

Specification of Letters Patent.

Patented Dec. 25, 1906.

Application filed March 7, 1905. Serial No. 248,922.

To all whom it may concern:

Be it known that I, JOHN C. McLAUGHLIN, a citizen of the United States, residing in Brooklyn borough, city of New York, in the county of Kings and State of New York, have invented certain new and useful Improvements in Type-Writing Machines, of which the following is a specification.

This invention relates to the kind of type-writing machines in which the ribbon is vibrated at each type-stroke to cover and uncover the printing-point, and specifically to means for enabling either color-band of a "polychromatic" ribbon to be brought into use at will.

The object of the invention is to produce for this purpose a simple, compact, inexpensive, durable, and easily-operated mechanism which will not be liable to get out of order.

In the well-known "Underwood" type-writing machine, upon which I illustrate my invention, it is the practice to employ a movable frame, called the "universal-bar" frame, which is reciprocated at each key-stroke, such frame having a part called the "universal" bar, against which the type-bars act. Mechanism extends in said reciprocating frame to a ribbon-carrier, such that as each type-bar approaches the platen the ribbon is thrown up, and while the type-bar recedes the ribbon drops. Usually a slotted arm is provided upon said reciprocating frame for the purpose of actuating said ribbon-vibrating members.

In carrying out my invention I provide means whereby such arm or actuator may be adjusted at will upon said reciprocating frame and independently thereof in such a manner that either the upper edge portion or lower edge portion of the ribbon may be brought into use. Said universal-bar frame is at the middle portion of the machine and inaccessible to the operator, and in order to effect the desired adjustment of the actuator conveniently I provide a rock-shaft, which extends to the side of the machine and is there provided with a finger-piece, which is readily accessible to the operator.

In the said Underwood machine it is customary to shift the platen up and down to enable capital types and small types to print, and it is also usual to shift the ribbon-carrier up and down with the platen. My improvements are so applied as to be effica-

cious in both printing positions of the platen and ribbon.

In the accompanying drawings, Figure 1 is a vertical section taken at about the central part of the machine from front to rear and 6c showing the platen, the ribbon, the ribbon-carrier, and the vibrating frame and connected parts. At this figure the parts are shown in normal position by the full lines, the dotted lines at the top portion of the figure showing the printing position of the ribbon. Fig. 2 is a plan of parts seen at Fig. 1. Fig. 3 is a front elevation showing principally the means for shifting the device which actuates the ribbon-vibrating members. Fig. 4 illustrates in 65 full and dotted lines the different positions to which said actuator may be shifted. Fig. 5 is an elevation of one of a pair of co-operative locking members, and Fig. 6 shows an elevation and plan of the other of said co-operative 70 members.

Type-bars 1 are thrown rearwardly against the front side of a platen 2, the impressions being made by means of an inking-ribbon 3, having a band 4 of black along its upper edge 80 and a band 5 of red along its lower edge, although other colors may be employed, and the invention is not limited to a ribbon having two colors only.

The ribbon is threaded through a carrier 85 6, which slides up and down between guides 78, and at its lower end is pivoted at 9 to a bent lever 10, which vibrates up and down to raise and lower the ribbon-carrier. The fulcrum or pivot of this lever is seen at 11, the 90 lever being pivoted to a bracket 12, fixed to a vertically-shiftable rail 13, the latter shifting up and down with the platen in the usual manner of the Underwood machine, together with the lever and the ribbon-carrier 6. Said 95 lever is operated by means of an arm or actuator 14, which is held by screws 15 16 upon a frame 17. Said frame vibrates forwardly and backwardly at each key-stroke in a well-known manner. It is supported at its rear 100 end upon links 18, and its forward end has a guiding-tongue 19, which slides in a fixed member 20 of the framework. This frame 17 moves backwardly as a type-bar approaches the platen and forwardly as the 105 type-bar recedes from the platen. The actuator 14 moves with said frame and has a slot 21 to engage a shoulder-screw 22, fixed upon an arm 23 of the lever 10, whereby said lever is vibrated. Said screw 22 is above the 110

lever-pivot 11, so that when said frame 17 and the actuator 14 move back the lever-arm 10 is thrown up, together with the ribbon-carrier and ribbon, to the dotted-line position 5 A at Fig. 1, and when the frame 17 returns to normal position the arm 10 falls, together with the ribbon-carrier 6 and the ribbon, so as to expose the printing.

The actuator 14 is shiftable backwardly 10 and forwardly upon the frame 17 and independently thereof, the screws 15 and 16 passing through slots 24 and 25, formed in a base portion 26 of said actuator and resting upon the frame 17. Said slots extend forwardly 15 and rearwardly and are of a length to permit sufficient movement of the actuator to vibrate the lever 10 and throw the ribbon-carrier 6 up and down to bring either color-band thereon into use, such movement being preferably limited by the ends of the slots 24, 25. To effect this shifting movement of the actuator, I mount upon the reciprocating frame 17 a rock-shaft 27, having at its outer end a finger-piece 28 and at its inner end crank 29, 20 which has a wrist 30 extending through the actuator 14 and capable of shifting the same forwardly and backwardly for purposes already described.

The actuator is locked in its forward and 30 backward positions by means of a pair of co-operative members 31, 32, the former fixed upon a bracket 33, into which said rock-shaft is journaled, said bracket being fastened by screws 34 upon said frame 17. The other member 32 is fixed by a set-screw 35 upon the rock-shaft 27 and is provided with a projection 36, which may enter either of a pair of holes 37, formed in the member 31, said locking members being held together by a 35 compression-spring 38, coiled around said rock-shaft, which is movable endwise sufficiently to permit disengagement of the locking members.

At Fig. 1 the ribbon mechanism is shown 45 in normal position, and the actuator 14 is adjusted to its rearward position, so that when a key is operated the ribbon-carrier will be thrown up far enough to cause the types to strike the lower or red band 5. The platen and rod 13 are shown in elevated position 50 for writing capital letters.

When it is desired to make black impressions upon the paper, the finger-piece 28 and shaft 27 are pulled out, so as to disengage 55 the locking member 32 from the co-operative member 31, and when the finger-piece 28 is turned to bring the projection 36 into engagement with the other hole 37, where it is held by the spring 38, such movement effecting 60 the shifting of the actuator from the full-line to the dotted-line position at Fig. 4, so that normally the ribbon will stand in dotted-line position B, Fig. 1, and when the type-bars are operated the types will print through 65 the upper or black band upon the ribbon

It will be seen that the entire mechanism for shifting the color of the ribbon is mounted upon the vibrating frame 17, thus conducing to simplicity of construction and economy of manufacture, the parts being all small and light, so that their weight is unobjectionable, and being also inexpensive to make and assemble, and not liable to get out of order.

When the platen 2 and the rail 13 are shifted down to enable the bottom or lower case 75 types to print, the pivot 11 goes down with the rail 13, and the screw 22 travels down in the slot 21 in the usual manner. The lever 10 and carrier 6 with the ribbon drop accordingly. Thus it will be seen that the color of 80 the writing may be changed as desired, and that both upper and lower case types will print upon a single color-band of the ribbon, according to the adjustment of the actuator 14.

Variations may be resorted to within the 85 scope of my invention, and portions of my improvements may be used without others.

Having thus described my invention, I claim—

1. In a visible-writing machine, the combination of a ribbon-carrier, a lever for vibrating said carrier, a reciprocating frame, an actuator upon said frame to operate said lever, means for shifting said actuator to different positions upon said frame to raise 95 and lower the ribbon, and means for detaining it in either position to which it is shifted, during the reciprocations of said frame.

2. In a visible-writing machine, the combination of a ribbon-carrier, a lever for vibrating said carrier, a reciprocating frame, an actuator upon said frame to operate said lever, manually-operable means for shifting said actuator upon said frame, to raise and lower the ribbon while said frame is stationary, and means for detaining said actuator 105 in either position to which it is shifted, during the reciprocations of said frame.

3. In a visible-writing machine, the combination of a ribbon-carrier, a lever for vibrating said carrier, a reciprocating frame, an actuator upon said frame to operate said lever, and manually-controlled means for shifting said actuator upon said frame so as to vary the printing position of the said carrier, and means upon said frame for locking 115 said actuator in either of a plurality of positions during the reciprocations of said frame.

4. In a visible-writing machine, the combination of a ribbon-carrier, a lever for vibrating said carrier, a reciprocating frame, an actuator upon said frame to operate said lever, and means including a finger-piece mounted upon said reciprocating frame, for moving said actuator independently of said 120 frame to raise and lower the ribbon.

5. In a visible-writing machine, the combination of a ribbon-vibrating lever, a reciprocating frame, an actuator mounted upon said frame for movement independently 13

- thereof, and means for locking said actuator in either of a plurality of positions upon said frame during the reciprocations of said frame.
5. In a visible-writing machine, the combination of a ribbon-vibrating lever, a reciprocating frame, an actuator mounted upon said frame for movement independently thereof, manually-operable means mounted wholly upon said frame, for releasing said actuator and moving it from one position to another on said frame and locking it in either position.
10. In a front-strike writing-machine, the combination with a slide movable up and down, of a lever to operate said slide, a reciprocating frame, a slide mounted upon said reciprocating frame and having a part to engage said lever, a crank connected to said slide to shift the same to and fro independently of said frame, and a finger-piece connected to said crank.
15. In a front-strike writing-machine, the combination of a ribbon-carrier movable up and down, a lever engaging said ribbon-carrier, a reciprocating frame, a slide mounted upon said reciprocating frame, and engaging said lever, a rock-shaft mounted upon said frame, and having a crank to engage said slide, and a finger-piece upon said rock-shaft.
20. In a front-strike writing-machine, the combination of a ribbon-carrier movable up and down, a lever engaging said ribbon-carrier, a reciprocating frame, a slide mounted upon said reciprocating frame and engaging said lever, a rock-shaft mounted upon said frame, and having a crank to engage said slide, a finger-piece for rock-shaft, and means for locking said rock-shaft in a plurality of positions.
25. In a front-strike writing-machine, the combination of a ribbon-carrier, movable up and down, a lever engaging said ribbon-carrier, a reciprocating frame, a slide mounted upon said reciprocating frame and engaging said lever, a rock-shaft mounted upon said frame, and having a crank to engage said slide, a finger-piece for rock-shaft, and means for locking said rock-shaft in a plurality of positions.
30. In a front-strike writing-machine, the combination of a ribbon-carrier, movable up and down, a lever engaging said ribbon-carrier, a reciprocating frame, a slide mounted upon said reciprocating frame and engaging said lever, a rock-shaft mounted upon said frame, and having a crank to engage said slide, a finger-piece for rock-shaft, and means for locking said rock-shaft in a plurality of positions.
35. In a front-strike writing-machine, the combination of a ribbon-carrier, movable up and down, a lever engaging said ribbon-carrier, a reciprocating frame, a slide mounted upon said reciprocating frame and engaging said lever, a rock-shaft mounted upon said frame, and having a crank to engage said slide, a finger-piece for rock-shaft, and means for locking said rock-shaft in a plurality of positions.
40. In a front-strike writing-machine, the combination of a ribbon-carrier, movable up and down, a lever engaging said ribbon-carrier, a reciprocating frame, a slide mounted upon said reciprocating frame and engaging said lever, a rock-shaft mounted upon said frame, and having a crank to engage said slide, a finger-piece for rock-shaft, and means for locking said rock-shaft in a plurality of positions.
45. In a front-strike writing-machine, the combination of a ribbon-carrier, movable up and down, a lever engaging said ribbon-carrier, a reciprocating frame, a slide mounted upon said reciprocating frame and engaging said lever, a rock-shaft mounted upon said frame, and having a crank to engage said slide, a finger-piece for rock-shaft, and means for locking said rock-shaft in a plurality of positions.
50. In a front-strike writing-machine, the combination of a ribbon-carrier, movable up and down, a lever engaging said ribbon-carrier, a reciprocating frame, a slide mounted upon said reciprocating frame and engaging said lever, a rock-shaft mounted upon said frame, and having a crank to engage said slide, a finger-piece for rock-shaft, and means for locking said rock-shaft in a plurality of positions.
55. In a front-strike writing-machine, the combination of a ribbon-carrier, movable up and down, a lever engaging said ribbon-carrier, a reciprocating frame, a slide mounted upon said reciprocating frame and engaging said lever, a rock-shaft mounted upon said frame, and having a crank to engage said slide, a finger-piece for rock-shaft, and means for locking said rock-shaft in a plurality of positions.
60. In a front-strike writing-machine, the combination of a ribbon-carrier, movable up and down, a lever engaging said ribbon-carrier, a reciprocating frame, a slide mounted upon said reciprocating frame and engaging said lever, a rock-shaft mounted upon said frame, and having a crank to engage said slide, a finger-piece for rock-shaft, and means for locking said rock-shaft in a plurality of positions.
65. In a front-strike writing-machine, the combination of a ribbon-carrier, movable up and down, a lever engaging said ribbon-carrier, a reciprocating frame, a slide mounted upon said reciprocating frame and engaging said lever, a rock-shaft mounted upon said frame, and having a crank to engage said slide, a finger-piece for rock-shaft, and means for locking said rock-shaft in a plurality of positions.
70. In a front-strike writing-machine, the combination of a ribbon-carrier, movable up and down, a lever engaging said ribbon-carrier, a reciprocating frame, a slide mounted upon said reciprocating frame and engaging said lever, a rock-shaft having a crank to engage said slide and mounted upon said frame, and a finger-piece for said rock-shaft.
75. In a front-strike writing-machine, the combination of a ribbon-carrier, movable up and down, a lever engaging said ribbon-carrier, a reciprocating frame, a slide mounted upon said reciprocating frame and engaging said lever, means limiting the movement of said slide, a rock-shaft having a crank to engage said slide and mounted upon said frame, and a finger-piece for said rock-shaft.
80. In a front-strike writing-machine, the combination of a ribbon-carrier, movable up and down, a lever engaging said ribbon-carrier, a reciprocating frame, a slide mounted upon said reciprocating frame and engaging said lever, means limiting the movement of said slide, a rock-shaft having a crank to engage said slide and mounted upon said frame, and a finger-piece for said rock-shaft.
85. In a front-strike writing-machine, the combination of a ribbon-carrier, movable up and down, a lever engaging said ribbon-carrier, a reciprocating frame, a slide mounted upon said reciprocating frame and engaging said lever, means limiting the movement of said slide, a rock-shaft having a crank to engage said slide and mounted upon said frame, and a finger-piece for said rock-shaft.
90. In a front-strike writing-machine, the combination of a ribbon-carrier, movable up and down, a lever engaging said ribbon-carrier, a reciprocating frame, a slide mounted upon said reciprocating frame and engaging said lever, means for locking said rock-shaft in a plurality of positions, said locking means including a fixed member and a coöperative member mounted upon said rock-shaft, one of said coöperative members having a projection and the other having recesses to receive the projection, and a spring normally pressing said coöperative members together.
95. In a front-strike writing-machine, the combination of a ribbon-carrier, movable up and down, a lever engaging said ribbon-carrier, a reciprocating frame, a slide mounted upon said reciprocating frame and engaging said lever, means for locking said rock-shaft in a plurality of positions, said locking means including a fixed member and a coöperative member mounted upon said rock-shaft, one of said coöperative members having a projection and the other having recesses to receive the projection, and a spring normally pressing said coöperative members together.
100. In a type-writing machine, the combination with a platen, a ribbon-carrier, and a ribbon-lever, all of said members being shiftable up and down together to enable different types to print, of a reciprocating frame, an actuator thereon mounted to slide, and having a slot to engage said lever to accommodate up-and-down shiftable movements, and manually-controlled means mounted upon said frame for sliding said actuator independently of said frame, to advance or retract said ribbon, and means for detaining said actuator in either of a plurality of positions upon said frame.
105. In a type-writing machine, the combination with a platen, a ribbon-carrier, and a ribbon-lever, all of said members being shiftable up and down together to enable different types to print, of a reciprocating frame, an actuator thereon mounted to slide, and having a slot to engage said lever to accommodate up-and-down shiftable movements, and manually-controlled means mounted upon said frame for sliding said actuator independently of said frame, to advance or retract said ribbon, and means for detaining said actuator in either of a plurality of positions upon said frame.
110. In a sight-writing type-writer, having a platen shifting to bring it into printing relation with upper-case characters and having a ribbon-interposing means which shifts with the platen to maintain its relation and normal operation during upper-case printing, an actuating means having a constant movement and connections through which said actuating means may be brought into engagement with the ribbon-interposing means and impart either of two different throws thereto at either of the different positions of the interposing means due to the shifting of the platen.
115. In a sight-writing type-writer, having a platen shifting to bring it into printing relation with upper-case characters and having a ribbon-interposing means which shifts with the platen to maintain its relation and normal operation during upper-case printing, an actuating means having a constant movement and connections through which said actuating means may be brought into engagement with the ribbon-interposing means and impart either of two different throws thereto at either of the different positions of the interposing means due to the shifting of the platen.
120. In a sight-writing type-writer, having a platen shifting to bring it into printing relation with upper-case characters and having a ribbon-interposing means which shifts with the platen to maintain its relation and normal operation during upper-case printing, an actuating means having a constant movement and connections through which said actuating means may be brought into engagement with the ribbon-interposing means and impart either of two different throws thereto at either of the different positions of the interposing means due to the shifting of the platen.
125. In a sight-writing type-writer, having a platen shifting to bring it into printing relation with upper-case characters and having a ribbon-interposing means which shifts with the platen to maintain its relation and normal operation during upper-case printing, an actuating means having a constant movement and connections through which said actuating means may be brought into engagement with the ribbon-interposing means and impart either of two different throws thereto at either of the different positions of the interposing means due to the shifting of the platen.
